UNITED STATES PATENT OFFICE.

GEORGE R. WEST, OF GRAPEVILLE, PENNSYLVANIA, ASSIGNOR TO FALK TOBACCO CO.,
OF NEW YORK, N. Y., A CORPORATION OF NEW YORK.

RECEPTACLE.

1,194,799.

Specification of Letters Patent. Patented Aug. 15, 1916.

Application filed November 13, 1915. Serial No. 61,288.

To all whom it may concern:

Be it known that I, GEORGE R. WEST, a citizen of the United States, residing at Grapeville, in the county of Westmoreland and State of Pennsylvania, have invented 5 certain new and useful Improvements in Receptacles, of which the following is a specification.

This invention relates to the subject of 10 receptacles adapted for the reception of tobacco products and other articles, and the primary aim of the invention is to produce a receptacle of the type stated in which the cover of the same is provided with novel 15 means that will prevent air or moisture gaining access to the interior of the receptacle, said means also serving as a cushion to prevent damage to the cover or the receptacle.

20 Simple and practical forms of the invention are shown in the accompanying drawings wherein—

Figure 1 is a perspective view of the improved receptacle. Fig. 2 is a fragmentary 25 perspective view of the cover for the receptacle. Fig. 3 is a fragmentary bottom plan view of the cover shown partly in section. Fig. 4 is a detail sectional view of the receptacle and cover shown assembled. Fig. 30 5 is a view similar to Fig. 4 showing a modified form of the invention.

The improved receptacle is especially adapted for use in connection with cigarettes and other tobacco products and it is preferred that the same be made of fragile 35 material and ornamented so that the same will be pleasing to the eyes of purchasers and of such a nature that when emptied of its original contents, may be used as an ornamental receptacle for various articles.

40 The invention contemplates in its general organization and in the various forms shown a body 1, and a cover 2. It is preferred that the receptacle and cover be rectangular in shape, and the cover 2 has a depending inset 45 flange 3 on its under surface, that conforms to the shape of the open upper portion of the body 1, and is adapted to fit within the upper portion of the receptacle in abutting 50 relation with the inner surface of the walls

of said receptacle, the portion 4 of the cover beyond the flange 3 resting on the upper edge of said walls.

The outer portions of the corners of the flange 3 are provided with notches 5 forming seats for holding a combined seal and cushion 6 in contact with and in surrounding relation to the said flange. The combined cushion and seal 6 is formed of a resilient material, and as shown in Figs. 1, 3 and 4 of the drawing may be a continuous 60 band of flat rubber, that will lie flat on the portion 4 of the cover beyond the flange 3 so that when the cover 2 is seated on the body 1, said cushion and seal 6 will be interposed 65 between the top edges of the walls of the body 1 and the cover 2, and thereby serve as a seal as well as to form a cushion that will prevent damage being done to the cover or body when the cover is being placed on 70 the body. It is to be understood, of course, that the notches 5 serve to prevent accidental displacement of the seal and cushion 6, such notches, as shown being in the form of corner recesses in which the seal and cushion seats, and are shaped so that no sharp edges are formed that might cut or otherwise damage the said seal and cushion.

75 By referring to the drawing it will be observed that the corner recesses 5 are of such a nature that the seal and cushion 6 is held perfectly flat at the corners thereby preventing said seal and cushion becoming twisted, or otherwise distorted from its normal flat condition.

80 In the modified form of the invention shown in Fig. 5 two of the combined seals and cushions are employed in connection with the cover 2, the seals being held in engagement with the forward portion of the 85 cover 2 and with the outer surfaces of the flange 3 so that a seal and cushion is interposed between the outer side of the flanges and the inner surface of the walls of the body 1, and between the cover 2, and the top 90 edge of the walls of the said body. In this form of the invention, as in the preferred 95 form, the seals are held in proper position by means of their engagement with the notches or grooves 5.

I claim as my invention:—

A receptacle comprising a rectangular body, a cover therefor having a depending flange that extends into and conforms to the contour of the body, said flange being provided with corner recesses, and a flat resilient seal and cushion surrounding the outer surface of the flange and having portions

seated in the corner recesses to hold said seal and cushion in a flat condition.

In testimony whereof I have affixed my signature in the presence of two witnesses.

GEORGE R. WEST.
